ELECTROMECHANICAL-CONVERSION
DEVICEFrederick Vinton Hunt, Belmont, and John Alvin
Pierce, Cambridge, Mass.

Application July 10, 1940, Serial No. 344,750

35 Claims. (Cl. 179—100.41)

The present invention relates to electro-mechanical-conversion devices, and more particularly to vibration-translating devices, such, for example, as are used for reproducing or recording sound with wax, shellac, lacquer, metal, and similar phonograph-record materials.

In Letters Patent 2,239,717, granted April 29, 1941, there is disclosed a new and improved phonograph reproducer that reproduces phonograph records with complete fidelity, encompassing the entire range of audible frequencies, with very low distortion, and with very small wear of the material of which the records are constituted.

An object of the present invention is to improve upon reproducers of the type described in the said Letters Patent.

A further object of the present invention is to provide a new and improved phonograph reproducer that shall be easy to fabricate and that shall be sufficiently simple in mechanical behaviour to allow a quantitative mathematical analysis of the behaviour and a quantitative engineering design in advance of actual construction.

The reproducer disclosed in the said Letters Patent employs viscous damping material that, however, may become subject to aging and deterioration. A further object of the present invention, therefore, is to provide a phonograph reproducer which shall require no viscous damping material.

Another object is to provide an electromechanical conversion device embodying a novel jack, or clamp, whereby the action of a screw in pressing together two pairs of conductors also provides a strong mechanical clamp, thereby relieving the conductors themselves of mechanical strain.

Other and further objects will be explained hereinafter, and will be particularly pointed out in the appended claims.

The invention will now be described in connection with the accompanying drawings, in which Fig. 1 is a plan of a phonograph reproducer embodying the invention, shown disposed in contact with the surface of a phonograph record; Fig. 2 is a section, upon a larger scale, taken upon the line 2—2 of Fig. 1, looking in the direction of the arrows; Figs. 3 and 4 are similarly enlarged sections, taken upon the lines 3—3 and 4—4, respectively, of Fig. 1, looking in the direction of the arrows; Fig. 5 is a fragmentary plan of a modification, the magnet and other parts being omitted, for clearness; Fig. 6 is a corresponding elevation, partly in section, upon the line 6—6 of Fig. 5, looking in the direction of the arrows; Fig. 7 is an underside plan of the forward portion of the embodiment illustrated in Figs. 5 and 6; Figs. 8, 9, 10 and 11 are sections taken upon the similarly numbered section lines

of Fig. 7; Fig. 12 is a plan, similar to the plan of Fig. 5, illustrating a preferred embodiment of the invention; Fig. 13 is a developed plan of the unitary ribbon inductor - and - mechanical - supporting member used in the embodiments of the invention illustrated in Figs. 12 to 18, inclusive; Fig. 14 is a section of the reproducer head, taken upon the line 14—14 of Fig. 12, looking in the directions of the arrows; Fig. 15 is a section of the jack for mounting the reproducer head of Figs. 12 and 14 on the tone arm, the section being taken upon the line 15—15 of Fig. 14; Fig. 16 is an underside plan of the reproducer head illustrated in Fig. 14; Figs. 17 and 18 are sections of the reproducer head, taken upon the lines 17—17 of Fig. 16 and 18—18 of Fig. 14, respectively, looking in the directions of the respective arrows; Fig. 19 is a schematic plan representing the structures shown in detail in previous views; Fig. 20 is a corresponding schematic elevation; Fig. 21 is an electric-circuit diagram equivalent to the mechanical system of Figs. 19 and 20; and Figs. 22, 23, 24 and 25 are symbolic graphs representing performance characteristics more fully described hereinafter.

25 A stylus needle 3, the lower end of which is adapted to be disposed in contact with the undulations in the sound track of a phonograph record 1, is mounted at the front end of a movable tone arm. As explained in the said Letters Patent, the stylus needle may be constituted of a permanent jewel, such as a sapphire or diamond. The reproducer support is shown comprising two substantially parallel spaced metal tubes 5 held together as a unitary structure, or as the single metal tube 81. These supports comprise the tone arm and are pivoted, as described in the said Letters Patent, to permit the tone arm to swing freely back and forth, and also up and down.

30 As illustrated in Figs. 1 to 4, the front open ends of the tubes 5 may be held together by a yoke 35, carried by an insulating bottom plate 78. The yoke 35 and plate 78 may be constituted of Bakelite. The plate 78 may support a high-intensity of U-shaped permanent magnet 54 having a north-pole piece 68, providing a north pole N, and a south-pole piece 70, providing a south pole S. A small stationary soft-iron pole piece 77 is held in place on the insulating plate 78 by a pin or screw 9. A permanent horse-shoe magnet 110 of somewhat different shape, having soft-iron pole pieces 112, and a centrally disposed pole piece 114, is shown in Figs. 12 to 18.

35 As explained in the said Letters Patent, the portion of the reproducer that more immediately carries the stylus 3, and which is more immediately driven thereby, is mounted at the front of the tone arm, partly in the spaces between the pole pieces 68 and 70 of Fig. 4, or in the spaces

between the pole pieces 112 of Fig. 18. It may be constituted of a pivotless-inductor dynamic-type device in the form of a substantially horizontally disposed single-turn or multiple-turn inductor, shown as the elongated loop 13 of Figs. 1 and 2 and at 38 in Figs. 5, 6, 16 and 18. The loop constitutes a combined electric circuit and mechanical support. The sides of the loop are shown disposed transversely in the magnetic field of the permanent magnet 54 or 110.

The inductor loop 38 shown in Figs. 5 to 18 is in the form of an interrupted cylindrical shell, provided with rear-end supporting arms 66, one at each end of the interrupted cylindrical shell.

In the modification shown in Figs. 1 to 4, the rear ends 66 of the loop 13 are secured to mounting blocks 80 that are held to the insulating bottom plate 78 by screws 64, and they may be connected to a transformer (not shown) by wires 58 and 60 that may be insulated from each other in any well known way. The inductor element is provided with an intermediately widened portion, bent into the form of a stiff conical shell 36 at the extreme forward or outer closed free end of the loop 13. Ribbon-like arms 82 and 84, of any desired length, connect the shell 36 to the ends 66 of the loop. The active portion of the loop thus extends throughout the length of the pole pieces 68 and 70.

As is further explained in the said Letters Patent and embodied in the devices here disclosed, the stylus 3 is rigidly mounted at the bottom apex tip of the cone 36, substantially normal to the substantially horizontal plane of the inductor loop, and the upper base of the cone is substantially in the plane of the inductor loop. The height of the cone provides the necessary leverage, and the cone shape provides a substantially maximum-stiffness lever for the mass of material employed for the purpose, inasmuch as a conical shell of given mass provides a structure of the maximum stiffness to connect the stylus point and a loop of given size. The conical shell 36 thus connects the stylus 3 and the loop driven thereby, to provide a very high ratio of stiffness to inertia, leading to small phase shift between the impressed motion and the electrical output, and correspondingly excellent transient response.

Whether constituted of a single loop as here illustrated or, where greater voltages are needed, a plurality of loops as described in the said Letters Patent, the inductor coil is easy to fabricate, since it may be made from a thin ribbon blank, as shown in Fig. 13, constituted of some electrically conducting metal, such as duraluminum or, preferably, coin silver, that may be punched from sheet stock. When bent into shape, the ribbon is substantially vertically disposed to provide great stiffness and rigidity.

In the modification of Figs. 1 to 4, the rear arms 66 of the loop are twisted out of the vertical plane toward the horizontal by (90- Δ) degrees, as illustrated in the sectional view of Fig. 3. As described in the said Letters Patent, but not illustrated here, the side arms 82 and 84 of the loop 13 and the upper or base portion of the conical shell 36 may be bent into the form of a U-shaped channel. The function of this channel form is to provide great rigidity of the forward portion of the inductor loop. In the modifications illustrated in Figs. 5 to 18, even greater rigidity is provided by securing the interrupted cylindrical inductor portion 38 of the loop about the cylindrical upper base portion 37, which is integral with and partakes of the rigidity of the conical shell

stylus support 36. This rigidity provides that the forward portion, or the inductor loop, which lies in the magnetic field, shall always move as a single whole, without relative vibration of the electromagnetically active portions of the loop.

5 On account of the disposition of the loop ends 66 in substantially the same plane as the remainder of the inductor loop, the active portion of the loop is very stiff for lateral forces applied in the 10 plane of the loop. However, because the loop ends 66 have the form of ribbons whose width is large in comparison with their thickness, the inductor loop has great flexibility for motion occurring about a longitudinally disposed axis of the loop. 15 When a lateral force or displacement is applied to the stylus 3 positioned at the apex of the conical shell 36, the only motion which the electromagnetically active portion of the loop can execute is a rotation about the longitudinally disposed axis, and because the inductor-loop structure has great flexibility for this torsional motion, the force required on the stylus 3 to produce this motion of the loop is extremely small.

The mass of the inductor-loop element, together with the conical shell and the sapphire stylus, may be made less than approximately 30 milligrams. Most of this mass, owing to the shape and disposition of the inductor loop, is concentrated close to the longitudinally disposed axis of vibration, so that the equivalent mass of the entire vibratory system, as viewed from the stylus apex as a driving point, may be less than about 5 milligrams. The mass reactance of the dynamical moving system, even at the highest frequencies, is thus so small that very small forces are required to hold the stylus in positive contact with the record groove. In consequence of the small mass reactance of the vibratory system, the wearing of even very soft record materials is minimized and the transient momentary deformation of the record material is so slight that very high frequencies are reproduced without appreciable translation loss.

45 A very light, unrestricted vibration-translating device is thus provided, adapted to vibrate about an axis which is quite rigid and stiff for lateral displacement in the plane of the loop, but which is very flexible, so as to move substantially freely, in torsion; a lateral vibrational displacement of the 50 stylus 3 below the plane of the loop is converted into a rotary motion of the stiffened front portion of the loop. No pivots are required to obtain the desired motion of the inductor loop since the longitudinal axis of vibration is established by the 55 inherent differential flexibilities obtained by means of the conformation of the mechanical-supporting-and-inductor loop itself. As the stylus 3 moves up and down, and to the right and the left, the stylus yields and moves freely in all directions, communicating the appropriate vertical or rotational motion to the inductor loop by virtue of the inherent flexibilities obtained by the conformation of the loop.

60 The loop 13 or 38 constitutes both the mechanical system to which the stylus 3 delivers its energy and the electric system for conveying the energy. A voltage is induced in the loop when the stylus needle 3 is caused to vibrate to drive the stylus support and, by conventional transformation, the 65 electrical energy may be delivered from the low-impedance loop to ordinary communication circuits. The conical stylus mount and the inductor loop are so light and have such great rigidity on account of their geometrical configuration that the 70 electromagnetically active system vibrates 75

freely as a rigid unit in response to the force exerted on the stylus by the sound track.

Sudden jars of the turntable or tone-arm mounting might be thought by some to be liable to cause the reproducer to bounce out of the record groove. As is explained and claimed in the said Letters Patent, the mass distribution and pivoting of the tone arm may be arranged in such a way as to avoid this difficulty.

As is further explained in the said Letters Patent, the stylus-supporting arm may be made sufficiently long so as to enable it to swing somewhat beyond the center of the record, thus reducing the error introduced by change in the tracking angle. The loop 13 is shown disposed at an angle to the direction of extension of the supporting arm to reduce the tracking angle to a minimum, or low, value.

As explained in the said Letters Patent, and described more fully in our published paper in the Journal of the Acoustical Society of America for July, 1938 (vol. 10, page 14), it is necessary for a phonograph reproducer stylus to be flexible in the vertical direction in order to avoid deforming the record material in the pinched sections of the groove. According to the present invention, the pressure exerted by the stylus needle 3 on the record and the mechanical impedance of the dynamical system for vertical motion are so small that, instead of tearing through the material of the record in the pinched sections of the groove, the stylus rises up slightly and passes over them without causing any damage; and this without failing to follow substantially the center line of the record groove. This results in the total elimination of all even harmonics in the lateral motion of the stylus needle 3. Such vertical motions would tend to produce a distortion voltage by virtue of the motion of the inductor loop in the magnetic field, but such distortion voltages are prevented from appearing in the output, according to the present invention, because the side arms 82 and 84 of the loop 13, or the corresponding side arms of the inductor portion 38, are both raised and lowered simultaneously. By virtue of the disposition of the magnetic field, as illustrated, the otherwise distortion-producing voltage is thus introduced into the two sides of the loop in opposite directions, and is simultaneously accurately cancelled out, so that only the voltage caused by the lateral motion of the stylus needle remains to produce the desired electrical output corresponding in facsimile to the recorded groove modulation.

According to the invention disclosed in the said Letters Patent and embodied in the modification illustrated in Figs. 1 to 4, damping is provided partly by a damping membrane 19 connecting the cone 36 at the closed, outer end of the loop to the pole piece 77 and lying within the loop 13, and partly by two similar membranes 21 and 23. The membrane 19 is disposed at the extreme forward end of the loop, at the points where the cone 36 is joined thereto, almost on the axis of rotation, where the amplitude of motion is least, and any effect of non-uniform elasticity of the material is minimized. The membranes 21 and 23 are disposed at the extreme ends of the loop, and connect the ends 66 of the loop 13 with the rear portions of the adjacent magnetic structure or the base 78, bridging the spaces between them. The membranes 21 and 23 absorb and prevent reflection of such undamped vibrations as may reach to these points.

The damping membranes 19, 21 and 23, in ad-

dition to providing the required damping of the free vibrations of the inductor loop induced by the stylus motion, provide a means for transmitting a portion of the force pressing the stylus 3 into contact with the record groove, the said force being produced by the net unbalanced weight of the reproducer head and tone-arm. Also described as a modification in the said Letters Patent, there was provided an auxiliary spring (not shown here) for transmitting this force pressing the stylus into contact with the record groove. It is undesirable to rely upon the mechanical strength of the said damping material to transmit this force on account of the possibility of cold-flow of the damping material, with consequent derangement of the relative positions of the reproducer parts.

According to the present invention, the rear portions of the vibratory loop are in the form of two flat ribbon members 66, each inclined to the horizontal by an angle Δ , as indicated in the sectional view of Fig. 3, to form between them a dihedral angle $(180-2\Delta)^\circ$. A sufficient elastic strength in the vertical direction may thus be secured to carry the said unbalanced weight. At the same time, and by virtue of the ribbon-like form of the members 66, there is no appreciable stiffening of the structure for rotational motion. By virtue of the inclination of the members 66 to the horizontal by the indicated angle, the same desirable features of rigidity for lateral displacement in the plane of the vibratory loop, and great flexibility in torsion about an axis line parallel to this plane, are secured, with the additional provision of a suitable vertical stiffness. This vertical stiffness can be altered by altering the said dihedral angle, and rotation takes place about a horizontal axis lying at the intersection of the two planes of the inclined ribbon members 66. The unbalanced weight of the reproducer head may thus be supported by the vertical stiffness developed by this inclination. The damping material has no function to perform except to provide damping and there is, therefore, no difficulty arising from cold-flow of the damping material, nor any necessity to provide additional auxiliary springs to transmit a vertical component of force.

In Figs. 5 to 11, the conical shell 36 is shown as separate from its inductor-and-elastic supporting ribbon, and as embodying the upper cylindrical section 37. It is, however, combined into a unitary vibratory structure with its supporting ribbon by wrapping an intermediate narrow portion 38 of the latter around the major portion of the periphery of the cylindrical section. The supporting ribbon is bent at its junction lines 45 with the cylindrical shell 37 to form the two substantially flat supporting and conducting members 66, hereinafter called the "back-flats." The cylindrical shell 37 is customarily insulated from the inductor 38 by the cement used to join them into a unitary structure, but this insulation is not important at this junction because the inductor 38 may be of high electrical conductivity while the cylindrical shell 37 is very thin and of low conductivity, and very little loss of output is brought about by imperfect insulation between them. The developed form of the unitary inductor and mechanical supporting member may be similar to that shown in Fig. 13. The preferred embodiment, illustrated in Figs. 12, 14 and 16, is the same in essence as that illustrated by Figs. 5, 6 and 7, except that the back-flats have been tapered to secure added stiffness of the transverse

compliance of the equivalent pivot. A magnetic field is to be provided in the structures of Figs. 5 to 11, the same as illustrated in Figs. 12 to 18, and hereinafter described. Of the unitary inductor-and-mechanical-supporting member, the narrow interrupted-cylindrical-shell portion 37, wrapped around the cylindrical shell 37 constitutes the inductor portion, while the widened supporting-arm portions 66, extending beyond the two junction lines 45, one at each end of the interrupted-cylindrical shell, constitute the elastic-conducting-and-supporting member. Tabs 46, shown rectangular in Fig. 7, but triangular in Fig. 13, extending beyond lines 43, provide portions for clamping, welding, or soldering to fixed conducting supporting elements 65.

The conductors 58 and 60 may be respectively connected to the supporting elements 65. The conducting leads 58 and 60 may be held to an insulating supporting block 71 by a screw 73. A supporting tube 75 is held on the tone arm by a screw 77, in a mating tube 83. The tube 75 carries the insulating supporting block 71. The tubes 75 and 83 may be clamped together by the screw 77. The tube 75, the supporting block 71, and the vibratory elements and the mounting supports carried thereby, may be removed from the tone arm by unscrewing the screw 77. The tube 75 contains the leads 58 and 60, insulated by the supporting block 71, and the tube 83 two corresponding spaced mating leads 85 and 87, insulated from the tube 83. The conductors 58, 60, 85 and 87 are thus disposed between the clamping members 75 and 83. The screw 77 extends into the tone arm through a slot 79 in the tube 75.

The end of the tone arm on which the reproducer head is mounted comprises an outer supporting tube 81 and an inner tube 83, in which is mounted the clamping screw 77. The two spaced conductors 85 and 87 are adapted to make contact with the corresponding conducting mating electrical leads 58 and 60 of the reproducer head. The inner tube 83 is split at its outer end, as illustrated at 89, Fig. 15. The tube 83 is insulated from the lead 60 and its mating tube 75 from the lead 58. When the clamping screw 77 is tightened, the two conductors 85 and 87 are pressed into intimate electrical contact with the respective mating lead conductors 58 and 60 from the reproducer head; at the same time, the force pressing these leads together acts to spread the split inner tube 83 into close mechanical contact with the outer shell 75 of the reproducer head. The single operation of tightening the screw 77 affords a good electrical contact between the leads and a strong mechanical attachment of the reproducer head on the tone arm without reliance on the electrical conductors for mechanical strength.

The operation of the reproducer may be better understood in connection with the schematic representations of Figs. 19 and 20, where the relatively short and wide back-flat supporting members 66 are presented as disposed in two planes intersecting along a line perpendicular to the plane of Fig. 20, as indicated at P. The back-flat members 66, as viewed in the horizontal plane of Fig. 19, may be disposed approximately at right angles to each other. This 90° angle is approximately the optimum angle for providing maximum transverse stiffness of the effective pivot with a low stiffness for torsional rotation of the inductor.

A structure is thus provided that is very rigid

for lateral displacement in the plane of Fig. 19, but very flexible in torsion about the said axial line through P in Fig. 20. As heretofore described in connection with Fig. 3, so also in Fig. 9 and Fig. 20, the angle Δ of inclination of the back-flat members 66 to the horizontal will provide the necessary vertical stiffness to transmit the force pressing the stylus 3 into contact with the record groove.

In connection with the features of the present invention that relate to provision for "positive tracking," we make particular reference to Fig. 2 of our said paper in the Journal of the Acoustical Society of America for July, 1938 (vol. 10, p. 14). There it is shown that the included angle of a record groove which is laterally modulated must change as the recording stylus executes a motion perpendicular to the record groove. In order for the motion of the stylus 3 to be entirely controlled by the modulation of the record groove, it will be obvious that at least a portion of the record groove on each side of the midline of the stylus 3 must be in continuous contact with the stylus at all times. Such a condition of positive guidance of the stylus is sometimes called "positive tracking" and it will be obvious that when this condition is satisfied the stylus needle 3, in executing the lateral motion corresponding to the record groove, must also execute a vertical motion as a result of the change in the included angle of the record groove.

The structures disclosed herein make provision for this vertical motion and the magnetic field, represented symbolically by the arrow H—H in Fig. 19, is symmetrically disposed, so that no net voltage is induced in the inductor by vertical motion of the stylus. In order to hold the stylus in positive contact with the record groove at all times, and for any modulation impressed upon the record groove, it is necessary that the vertical compliance afforded by the elastic supporting members 66 fall within certain limits. These limits are determined by the consideration that the force necessary to deflect the stylus vertically from its equilibrium position by about 0.01 inch should be capable of imparting to the effective mass of the vibratory element for vertical motion an acceleration of about five hundred times that due to gravity. In a similar way, the desirable value of compliance for transverse motion of the stylus must be so chosen that the maximum displacement from equilibrium produced by low-frequency modulations of the record groove will not require transverse forces greater than that pressing the stylus in contact with the said record groove. For typical applications, the foregoing indicates that the transverse mechanical compliance at the stylus should lie between one and two times the mechanical compliance at the stylus for vertical motion.

The dimensional proportions and the disposition of the back-flat members 66 necessary to secure this desirable proportion of transverse and vertical compliances may be explained in connection with the experimental curves of Figs. 22 and 23. Reference may also be made to Figs. 8 and 11, showing, respectively, the angle α_1 formed between the plane containing the intersection of the member 66 and the cylinder 37 (see junction line 45 in Figs. 7 and 13) and a plane perpendicular to the axis of this cylinder, and the angle α_2 formed between the plane containing the tab 40 and the member 66 at its point of attachment to the support (see junction line 43 in Fig. 13) and the plane of the lower face 93 (Fig. 11) of

the supporting block 71 (Fig. 6). The face 93 of the supporting block 71 may be but is not necessarily in a plane perpendicular to the axis of the cylinder 37. The back-flats 66 indicated in Fig. 19 may be twisted out of a plane through the use of an angle α_1 (Fig. 8) at the point of attachment of the back-flats to the cylindrical section, different from the angle α_2 (Fig. 11) formed at the rear of the back-flats, where the back-flat member is attached to the mounting blocks.

In actual practice, it is not necessary that the axis of vibration be strictly parallel to the surface of the record 1. In the mathematical treatment based on Figs. 19 and 20, however, such parallelism has been assumed for convenience. An important advantage is gained by inclining the axis of vibration with respect to the record surface inasmuch as such inclination may bring the point of attachment of the back-flats 66 closer to the record surface. This has the advantage of providing that when the stylus is deflected upward the component of the resulting relative motion along the record groove is reduced. Moreover, there is inevitably some frictional drag induced by the passage of the record groove under the stylus tending to deform the elastic support for the conical shell. If this deformation is present to any considerable extent, a to-and-fro motion of the stylus along the direction of motion of the record groove may be excited in a manner similar to that in which a violin string is set into vibration by the gliding bow.

This to-and-fro motion of the stylus apex in, and along the direction of, the record groove and the resulting motion of the inductor portion of the vibratory element produce no electrical output by virtue of the symmetrical disposition of the magnetic field. However, this motion has the effect of superimposing a fluctuation upon the uniform linear velocity of the record groove and impressing upon the electrical output of the reproducer a flutter or frequency modulation. In the present invention, we disclose and describe a method of disposing the back-flat members 66 through choice of the angles α_1 and α_2 , as will be described below, and of shaping these members so that a very low mechanical compliance for longitudinal motion of the stylus is secured. It is possible to restrain this longitudinal motion of the stylus along the record groove in several other ways such as, for example, by providing a flexible wire or ribbon member. We have found that the longitudinal motion of the stylus may be damped effectively by using a restraining member comprising a thin filament or block of a viscous damping material 22, such as Viscaloid, rubber, Vistinex or other plastic, attached to the conical shell near the stylus apex and extending therefrom to the fixed point of attachment 20 supported from the insulating block 71, as illustrated in Figs. 6 and 7. Another and preferred modification of the restraint for the longitudinal vibration of the stylus may take the form of a thin film of elastic material 25 surrounding the apex of the conical shell above its point of contact with the record groove and cemented to a button-like projection 27 on the bottom of the mounting plate 78 shown in Fig. 2, or similarly attached to the bottom plate of a protective housing (not illustrated) surrounding the reproducer head pictured in Figs. 12 to 18. Such an elastic film may also serve the purpose of preventing dust and small particles of extraneous material

from entering the protective housing where it might enter the narrow air gap in the magnetic circuit and interfere with the satisfactory operation of the reproducer. We have found the following described disposition of the back-flats to provide sufficient stiffness for the longitudinal motion of the stylus to make these auxiliary provisions unnecessary in most cases. However, for reproducers or vibration-translating devices constructed according to the present invention but with dimensions different from those we have used in our experimental work, or in devices designed for other frequency ranges, these auxiliary restraints may be desirable, and our experiments and our analysis have indicated the adequacy of the mentioned methods for avoiding such difficulties.

The term "back-flat," throughout this description, has been used to refer to the elastic-supporting-and-conducting members 66, whether or not these are in a single plane. In the simplified case, in which

$$\alpha_1 = \alpha_2 = \Delta = 0$$

the back-flat members lie in the plane of the mounting face 93. Under these conditions, a rotation of the conical shell 36 about the axis through the line P (see Fig. 20) formed by the intersection of the planes of the back-flats (and, therefore, in the plane of the back-flats, since they are in this case horizontal) involves bending of the back-flat members 66 of the fixed-fixed type. By "fixed-fixed type" is meant that form of elastic deformation of the ribbon-like "beams" in which the end portions are constrained to remain approximately parallel to each other. On the other hand, for a vertical displacement of the stylus apex 3, the bending of the back-flats 66 is of the fixed-free type, as in an ordinary cantilever beam loaded at one end. If the effective lengths of the back-flats are the same for these two types of deformation, the compliance C_v for vertical motion would be approximately eight times the compliance C_t for transverse motion of the stylus. The above-described considerations, however, have indicated that this would provide an undesirable relation between the vertical and transverse compliances, and that it is desirable in a phonograph reproducer that the compliance for transverse motion of the stylus tip should be between one and two times that for vertical motion of the stylus tip.

Now, if the angle α_1 at the front of the back-flat members 66 is made different from zero, and the vertical and the transverse compliances at the stylus tip are measured and plotted as a function of the angle α_2 at the rear of the back-flat members 66, experimental curves are obtained similar to those shown by the solid lines of Fig. 22. In general, the vertical compliance C_v decreases rapidly as the angle α_2 is increased from zero toward ninety degrees. On the other hand, the torsional compliance C_t increases slowly as α_2 is first increased from zero, and displays a broad maximum at some angle α_2 approximately equal to α_1 , this equality occurring when the back-flat members 66 become substantially plane. This indicates that for a range of values of α_2 , the rear angle of the back-flats, the transverse compliance may be greater than the vertical compliance, as required for satisfactory operation of the reproducer. If a different and larger angle α_1 is chosen, such as α_1' , Fig. 22, the vertical compliance C_v is reduced for all values of α_2 , as indicated by the dashed curve C_v' of Fig. 22. For

this larger value of front angle α_1' , the torsional compliance C_t again displays a broad maximum at a higher value of α_2 , again approximately equal to the increased value of the angle α_1' . On the other hand, if the angle α_1 be chosen too small, it may be that the maximum of the curve of transverse torsional compliance occurs at so small a value of α_2 that the vertical compliance C_v is greater than the compliance C_t for all values of α_2 , as indicated in Fig. 23. It will be seen from these figures that it is possible to select values of α_1 and α_2 such that any desirable ratio between transverse and vertical compliance may be secured in the resulting structure. Having secured a desirable ratio between these compliances, their absolute magnitudes may be made to have desired values by an appropriate selection of the width and the thickness of the back-flats 66.

It may be pointed out also that an increase in the front angle α_1 at the point of attachment of the back-flat 66 to the conical shell 36 provides a desirable stiffening of this junction for the type of deformation described above as a consequence of the longitudinal frictional force along the record groove. If α_1 is increased too far toward 90°, the transverse stiffness of the effective pivot would be undesirably reduced. Our measurements have indicated that the angle α_1 may be chosen intermediately, such as about 25°, so that high transverse stiffness of the effective pivot is secured while at the same time a high degree of stiffness, or very low compliance C_L , is provided for longitudinal forces at the stylus apex. The measurements indicated by the curves of Fig. 22 further indicate that the rear angle α_2 at the point of attachment of the back-flats on their mounting blocks may be chosen independently to yield suitable ratios of transverse and vertical compliance at the stylus apex. We have found a suitable angle α_2 to be about 6°, and a suitable thickness of the back-flats to be about .0015 inch. It follows that all of the elastic compliances affecting the performance of the reproducer, for example, the transverse pivot compliance and the transverse, vertical and longitudinal compliances at the stylus apex, may be controlled and given suitable values by the described shape and disposition of the combined electrical and mechanical supporting members 66.

Further analysis of the mechanical behaviour of the structure symbolized in Figs. 19 and 20 may be made by writing the LaGrangian equations for the mechanical system represented by these Figs. 19 and 20. For this purpose, the following symbols may be used:

g is the distance from the apex of the stylus to the center of gravity of the vibratory system; h is the distance from the stylus apex to a line through P perpendicular to the plane of Fig. 20 and corresponding, if $\alpha_1 = \alpha_2$, to the intersection of the planes containing the back-flats or, if $\alpha_1 \neq \alpha_2$, to the line representing the axis of rotation determined by the elasticity of the back-flats alone; m is the total mass of the vibratory system; I is the moment of inertia of the vibratory system about an axis perpendicular to the plane of Fig. 20, and passing through the stylus apex; C_p is the transverse compliance in centimeters per dyne of the equivalent pivot established by the differential rigidity of the back-flats 66; C_r is the rotational compliance, in radians per dyne-centimeter, providing the restoring torque for angular displacements of the vibrator about the equivalent pivot;

y is the transverse displacement of the stylus apex from its equilibrium position induced by the displacement of the center line of the record groove (y is not illustrated in Fig. 20, because the stylus is there shown as occupying its equilibrium position);

x is the equivalent displacement from equilibrium of the inductor portion transverse to the magnetic field. (x is not illustrated in Fig. 20 because Fig. 20 represents the equilibrium condition); and

y' and x' represent the time derivatives of y and x , respectively, that is, the velocities of the corresponding displacements.

The solution of the differential equations describing the motion of the system may be represented by the electrical circuit of Fig. 21. In this circuit, if a constant-current generator, representing an impressed transverse velocity of the groove center line, is impressed on the circuit at the left-hand terminals 95, 97, the indicated current x flowing in the right-hand mesh represents the velocity of displacement of the inductor portion of the loop transverse to the magnetic field and, therefore, it is proportional to the voltage induced in the inductor. The elements of this equivalent electric circuit have the values indicated adjacent thereto, in accordance with the solutions of the differential equations.

Analysis indicates that the induced voltage constituting the output is proportional to

$$\frac{mg(\omega_0^2 - \omega^2)}{I(\omega_0^2 - \omega^2)} \quad (1)$$

where

$$\omega_0^2 = \frac{h}{gmC_p},$$

$$\omega^2 = \frac{h^2 C_0 + C_p}{IC_0 C_p},$$

ω is the angular frequency of the impressed transverse displacement y .

The performance indicated by this expression is represented by the symbolic curves of Figs. 24 and 25, in which the dashed lines at the critical frequencies ω_2 and ω_0 represent, respectively, infinite and zero values. In practice, some viscous damping is inevitable in a realizable structure so that these infinite or zero values never occur.

The important conclusion to be drawn from this mathematical analysis is that the structure may be so designed that the critical frequencies ω_2 and ω_0 may be made to coincide. In such a case, the corresponding terms involving ω_2 and ω_0 in Equation 1 cancel, and the frequency response of the reproducer is perfectly uniform up to frequencies so high that the assumptions upon which the equivalent electrical and mechanical systems are based no longer hold. This frequency, in practical realizable structures, lies well beyond the audible range of frequencies.

Further analysis of the conditions necessary to make $\omega_0 = \omega_2$ yield the physical interpretation that the axis of percussion of the vibratory system as a whole should be made to coincide with the elastically determined axis passing through P at the distance h from the stylus apex. Thus, if the line through the stylus apex perpendicular to Fig. 20 and the axis of rotation through P defined by the elasticity of the back-flats 66 are conjugate centers of oscillation for impulsive forces applied either at the stylus apex or at this axis through P, the response of the reproducer will be perfectly uniform with respect to fre-

quency without any necessity for the provision of damping materials.

This desirable relationship may be further explained by calling attention to the fact that in most textbooks on "Mechanics" (see references below) the terms "center of percussion" and "center of oscillation" are discussed in connection with the motion of a rigid body having a fixed and immovable pivoting axis. The center of percussion is then analyzed as that point at which the body may be struck an impulsive blow without causing any force reaction on the pivot transverse to the line joining the pivot and the point of application of the impulsive force. It is further shown in these textbooks that if the impulsive force is applied at the previously immovable pivoting point, then the previous point of application is an instantaneous center of oscillation for the resulting motion; thus the previous pivoting point and the previous point of application are conjugately related and each is an instantaneous center of oscillation for impulses applied at the other.

Now, in the present instance, as in all prior-art vibration-translating devices, the pivot is not perfectly immovable but has, for transverse forces, an elastic compliance whose mechanical impedance is not negligible in comparison with the mass reactance of the vibratory system at the higher frequencies of excitation. If, therefore, the mass distribution of the vibratory system were such that the stylus apex or point of application of the impulsive forces were not a center of percussion with respect to the elastic pivot, then transverse force reactions would occur at the pivot upon the application of such impulsive vibromotive forces at the stylus apex. Since the vibrator has inertia, these force reactions at the pivot would be able to excite resonance oscillations whose frequency is determined by the mass and dimensions of the vibrator and the elastic pivot compliance. The said resonance oscillations comprise a transverse motion of the effective pivot and hence, by cyclically altering the relative transverse displacements of the stylus and the pivot, produce cyclic motion of the inductor portion transverse to the magnetic field. The effect of these motions on the electrical output is exhibited by the frequency-dependent terms in the response Equation 1. In the previous Letters Patent referred to above, these spurious resonance oscillations are controlled and damped by the provision of damping material, shown in Figs. 1 and 2 herewith at 19, 21 and 23, positioned so as to have the maximum damping effect on the undesired spurious oscillations and a minimum effect on the desired vibrations caused by the modulation of the record groove. Some prior-art devices have sought to avoid the difficulties introduced by these oscillations by using such rigid and, therefore, massive construction that the oscillation frequencies are above the useful range; but it is an object of this disclosure to show how, even with extremely light constructions of the vibratory system and even though the resonant oscillation frequencies fall within the useful range of reproduction, the effect of these oscillations may be avoided so that there is no necessity of providing any damping material to control them. For if the mass distribution of the vibratory system is chosen so that the elastic pivot is a center of oscillation conjugate to the stylus apex as a driving point, no force reactions occur at the pivot to excite the resonance oscillations and the corresponding fre-

quency-terms in the response Equation 1 cancel out as above mentioned.

By equating the above defining expressions for ω_2 and ω_0 , we may solve for the moment of inertia of the corresponding uniform-response vibrator, as follows:

$$I = mgh \left(1 + \frac{C_p}{h^2 C_\theta} \right) \quad (2)$$

10 The transverse pivot compliance C_p is usually very much smaller than the torsional compliance C_θ multiplied by h^2 . This expression therefore may be written in the following approximate form:

$$15 \quad \frac{I}{m} = gh \quad (3)$$

It follows that the product gh is equivalent to the square of the radius of gyration of the vibratory element about the stylus apex or point of application of the impressed force, and this is, therefore, a necessary condition for the design of a uniform-response vibratory system. Since the geometric mean of two quantities is defined as the square root of their product, this necessary condition may also be described by stating that the radius of gyration of the vibratory element, about the stylus apex, must be the geometric mean of the distance from the stylus apex to the center of gravity of the vibrator and the distance from the stylus apex to the elastically-determined pivoting axis.

Inasmuch as the mechanical structure, as idealized for mathematical analysis, is not particularized in any manner to restrict its application to phonographic apparatus, any rigid-body vibratory system having distributed mass and supported by an elastically constrained pivot, real or equivalent, falls within this mathematical analysis.

If all portions of such a distributed system are intended to move in exact correspondence with a velocity having any desired frequency and impressed at some particular point, then this point and the equivalent elastic pivot should form conjugate centers of oscillation. The term "conjugate centers of oscillation" is well understood in text books on "Mechanics" and refers to the phenomenon whereby an impulsive force applied at one of the centers and perpendicular to the line joining the two centers of oscillation produces about the conjugate center a purely rotational motion. (See, for example, "Introduction to Theoretical Physics," by L. Page, pp. 115-116, published by Van Nostrand, 1938, or "Handbook of Engineering Fundamentals," by O. W. Eshbach, pp. 4-41 to 4-42, published by Wiley, 1936.) These terms will be understood to describe the motion of the vibratory system insofar as it is controlled alone by the effects of inertia and it may further be understood that only these inertial effects are significant in determining the motion for impressed velocities at very high frequencies. For this reason, the conjugate center of oscillation may be referred to as an inertial axis or an axis of percussion, as distinguished in the above description from the axis of vibration for excitation at low frequencies which is determined by the elasticity of the supporting means.

60 The preceding analysis may therefore be summarized by stating the requirement that the elastic axis must coincide with the inertial axis for uniform response at all exciting frequencies.

In the preferred embodiment of the invention shown in Figs. 12 to 18, the vibratory element

differs from that of Figs. 5 to 11 by a tapering of the backflats 66, as before stated, from a narrow portion at the junction line 45 to a wider portion at the junction line 43. This tapering provides a reduction in the transverse-pivot compliance C_b , which serves to increase the values of the critical frequencies ω_2 and ω_0 , and thereby renders the reproducer uniformly responsive over a wider range of impressed frequencies. In this modification, the leads 58 and 60 from the reproducer head are continued over the lower face 93 of the supporting block 71 and form the mounting elements corresponding to the blocks 65 of Figs. 5 to 11, to which the mounting tabs 40 are attached. In these figures, a magnetic circuit is also illustrated comprising the horse-shoe 110 of hard, permanent magnetic material, seated upon soft-iron pole shoes 112. The pole-shoes 112 and the central pole piece 114, which may be of soft iron or preferably of a hard magnetic material, are attached to a brass block 116, which serves to attach the magnetic structure to the insulating block 71 by the screws 118, and to hold the magnetic circuit in appropriate relation to the inductor portion of the vibratory system.

Further modifications and changes will occur to persons skilled in the art, and all such are considered to fall within the spirit and scope of the invention, as defined in the appended claims.

What is claimed is:

1. Vibration-translating apparatus comprising a vibratory element having conjugate centers of oscillation, means for applying vibratory impulses at one of the centers, movable inductor-and-elastic supporting means for deriving inductively an electric signal from the vibration of the vibratory element and for supporting the element to vibrate about substantially the conjugate center in response to vibratory impulses applied at the said one center, and means for establishing a magnetic field in which the movable inductor means moves.

2. Vibration-translating apparatus comprising a vibratory element, movable inductor-and-elastic-supporting means for deriving inductively an electric signal from the vibration of the vibratory element and for providing an effective elastic pivot for low-frequency vibrations and a distribution of mass for the element such that the radius of gyration of the element about the point of application of the exciting force is substantially the geometric mean of the distance from the said point of application to the center of gravity of the element and the distance from the said point of application to the axis through the said effective pivot, and means for establishing a magnetic field in which the movable inductor means moves.

3. Vibration-translating apparatus comprising a vibratory element having a mass m and provided with an apex at a distance g from the center of gravity thereof, the element having elastic-supporting members adapted to provide an axis of rotation at a distance h from the apex and having a moment of inertia I about an axis through the apex parallel to the first-named axis substantially equal to

$$I = mgh \left(1 + \frac{C_p}{h^2 C_b} \right)$$

where C_p is the transverse compliance of the equivalent pivot established by the elastic-supporting means and C_b is the rotational compliance about the effective pivot provided by the said elastic-supporting means.

4. Vibration-translating apparatus comprising

a stylus, inductor means, means whereby the stylus is connected to the inductor means, and supporting means for the inductor means comprising metallic ribbons disposed at an angle to each other and the planes of which intersect substantially along a line that constitutes a longitudinal axis of vibration of the inductor means.

5. Vibration-translation apparatus comprising an inductor loop of interrupted cylindrical shell form, a cone-shaped stylus support along the base of which the interrupted-cylindrical loop is secured to provide rigidity, and supporting arms, one at each end of the interrupted cylindrical loop.

6. Vibration-translation apparatus comprising an inductor loop of interrupted cylindrical-shell form, a cone-shaped stylus support along the base of which the interrupted-cylindrical loop is secured to provide rigidity, and supporting arms, one at each end of the interrupted cylindrical loop, the arms being disposed substantially in planes inclined to one another.

7. Vibration-translation apparatus comprising an inductor loop of interrupted cylindrical-shell form, a cone-shaped stylus support along the base of which the interrupted-cylindrical loop is secured to provide rigidity, and supporting arms, one at each end of the interrupted cylindrical loop, the arms being disposed substantially in planes inclined to each other, and the line of intersection of the planes constituting a longitudinal axis of vibration of the inductor loop.

8. Vibration-translation apparatus comprising an inductor loop of interrupted cylindrical-shell form, a cone-shaped stylus support along the base of which the interrupted-cylindrical loop is secured to provide rigidity, and supporting arms, one at each end of the interrupted cylindrical loop, the supporting arms comprising sections of warped surfaces providing for a transverse compliance of the stylus apex one to two times larger than the vertical compliance of the stylus apex.

9. Vibration-translation apparatus comprising a stylus, inductor means, means whereby the stylus is connected to the inductor means, and supporting ribbons for the inductor means comprising sections of warped surfaces providing for a ratio of transverse to vertical compliance of between one and two.

10. Vibration-translation apparatus comprising a stylus, inductor means, means whereby the stylus is connected to the inductor means, and supporting ribbons for the inductor means comprising sections of warped surfaces providing for a ratio of transverse to vertical compliance of between one and two, the supporting means comprising arms disposed substantially in planes inclined to each other.

11. Vibration-translation apparatus comprising a stylus, inductor means, means whereby the stylus is connected to the inductor means, and supporting means for the inductor means comprising sections of warped surfaces providing for a ratio of transverse to vertical compliance of between one and two, the supporting means comprising arms disposed substantially in planes inclined to each other, and the line of intersection of the planes constituting a longitudinal axis of vibration of the inductor means.

12. Vibration-translation apparatus comprising a stylus, a support for the stylus and a combined mechanical-electrical connector-jack for supporting the stylus support and the stylus supported thereby, comprising two mating portions carried by the jack containing mating electrical leads in-

sulated from the mating portions, and means for simultaneously clamping together the mating electrical leads and the mating portions.

13. Phonographic apparatus comprising a stylus adapted to be disposed in contact with a record groove, combined inductor-and-elastic-supporting means, the said supporting means comprising two ribbon members providing at the stylus simultaneously a large compliance for transverse motion, a compliance for vertical motion lower than the first-named compliance, and a compliance for longitudinal motion lower than the first two named compliances.

14. Phonographic apparatus comprising a stylus adapted to be disposed in contact with a record groove, combined inductor-and-elastic-supporting means, the said supporting means comprising two ribbon members providing at the stylus simultaneously a large compliance for transverse motion, a compliance for vertical motion lower than the first-named compliance, and a compliance for longitudinal motion lower than the first two named compliances, and having the vibrational axis determined by the inertia of the parts coincident with the axis determined by the elastic supporting means.

15. Vibration-translating apparatus comprising a stylus, a stylus support comprising a conical shell having an integral cylindrical section at its base, movable inductor-and-elastic-supporting means attached to the cylindrical section constituting the mechanical system to which the stylus delivers energy and the electrical system for conveying the energy, and means for establishing a magnetic field transverse to the inductor-and-elastic-supporting means, the inductor-and-elastic-supporting means being unitary to constitute the sole support for the conical shell and being rigid to move in the magnetic field as a single whole without relative vibration of the electromagnetically active portions of the inductor means.

16. Vibration-translating apparatus comprising a stylus, a stylus support comprising a conical shell having an integral cylindrical section at its base, inductor means attached to the cylindrical section, means for establishing a magnetic field transverse to the inductor means, and elastic supporting means comprising two metallic ribbons attached to the cylindrical section at junction lines forming equal angles with a plane perpendicular to the axis of the cylinder and attached at their other ends to supporting means on junction lines forming equal, but smaller than the first-named, angles with the said plane.

17. Vibration-translating apparatus comprising a stylus, a stylus support comprising a conical shell having an integral cylindrical section at its base, inductor means attached to the cylindrical section, means for establishing a magnetic field transverse to the inductor means, and elastic-supporting means comprising two metallic ribbons attached to the cylindrical section at junction lines forming angles of about 25° with a plane perpendicular to the axis of the cylinder and attached at their other ends to supporting means on junction lines forming angles of about 6° with the said plane.

18. Vibration-translating apparatus comprising a stylus, a stylus mounting, and elastic-supporting means for the stylus mounting comprising two only ribbon members disposed to provide mechanical compliances at the stylus such that the compliance for transverse motion is larger than the compliance for vertical motion which, in turn,

is larger than the compliance for longitudinal motion.

19. Phonograph apparatus comprising a stylus adapted to be disposed in contact with the sound track of a record, a support for supporting the stylus in contact with the sound track, the support having a rear portion fixed at one end and a movable portion carried at the other end, and means for mounting the stylus at the free end of the movable portion only to constitute the movable portion the sole support for the stylus, the vibratory axis established by the support being disposed substantially at the center of oscillation conjugate to the point of contact between the stylus and the sound track.

20. Phonograph apparatus comprising a stylus adapted to be disposed in contact with the sound track of a record, a support for supporting the stylus in contact with the sound track, the support having a rear portion fixed at one end and a movable portion carried at the other end, and means for mounting the stylus at the free end of the movable portion only to constitute the movable portion the sole support for the stylus, the movable portion being shaped to prevent substantial mechanical deformation thereof in response to movement of the stylus along the sound track, and the rear portion being flexible in order that it may flex mechanically in response to movement of the stylus along the sound track, thereby to cause the movable portion to move substantially as a whole in response to movement of the stylus along the sound track, the vibratory axis established by the support being disposed substantially at the center of oscillation conjugate to the point of contact between the stylus and the sound track.

21. Phonograph apparatus comprising a stylus adapted to be disposed in contact with the sound track of a record, means for creating a magnetic field, a support for supporting the stylus in contact with the sound track, the support having a rear portion fixed at one end and a movable inductor portion carried at the other end, and means for supporting the stylus at the free end of the inductor portion only to constitute the inductor portion the sole support for the stylus, the inductor portion being disposed in the magnetic field in order that electric currents may flow therein in response to movement of the stylus along the sound track, the inductor portion being shaped to prevent substantial mechanical deformation thereof in response to movement of the stylus along the sound track, and the rear portion being flexible in order that it may flex mechanically in response to movement of the stylus along the sound track, thereby to cause the inductor portion to move substantially as a whole in response to movement of the stylus along the sound track, the vibratory axis established by the support being disposed substantially at the center of oscillation conjugate to the point of contact between the stylus and the sound track.

22. Phonograph-reproducing apparatus comprising a stylus, vibratory supporting means for the stylus, and electrical means for deriving an electrical voltage from the vibrations of the supporting means, the supporting means being disposed to provide great flexibility for lateral motion of the stylus, whereby the recorded sounds may be faithfully reproduced in the electrical output, and the supporting means being disposed so as to provide great flexibility for vertical motion of the stylus without producing a corresponding electrical output, thereby removing the prin-

cial distortion products otherwise present in the electrical output, the vibratory axis established by the support being disposed substantially at the center of oscillation conjugate to the point of application of vibratory forces upon the stylus.

23. Phonograph-reproducing apparatus comprising a stylus, vibratory supporting means for the stylus, and electrical means for obtaining an electrical voltage in response to lateral motion only of the stylus, said supporting means being disposed to provide a low mechanical impedance for vertical motion, whereby the stylus may be supported substantially upon both side walls of the record groove simultaneously and at all times without damage to the record, the vibratory axis established by the support being disposed substantially at the center of oscillation conjugate to the point of application of vibratory forces upon the stylus.

24. Vibration-translating apparatus comprising a vibratory element, a support for supporting the element, the support having a rear portion fixed at one end and a movable portion carried at the other end, means for mounting the element at the free end of the movable portion only to constitute the movable portion the sole support for the element, the movable portion being shaped to prevent substantial mechanical deformation thereof in response to vibratory movement of the element, and the rear portion being flexible in order that it may flex mechanically in response to vibratory movement of the element, thereby to cause the movable portion to move substantially as a whole in response to vibratory movement of the element, the vibratory axis established by the support being disposed substantially at the center of oscillation conjugate to the point of application of vibratory forces upon the element.

25. Vibration-translating apparatus comprising a vibratory element, vibratory supporting means for the element, electrical means for deriving an electrical voltage from the vibrations of the supporting means, the supporting means being disposed to provide great flexibility for lateral motion of the vibratory element and being disposed so as to provide great flexibility for vertical motion of the element without producing a corresponding electrical output, the vibratory axis established by the support being disposed substantially at the center of oscillation conjugate to the point of application of vibratory forces upon the element.

26. Phonographic apparatus comprising a stylus adapted to be disposed in contact with a record groove, and combined inductor-and-elastic-supporting means comprising two ribbon members disposed at an angle to each other, the line of intersection of the planes of the ribbon members substantially coinciding with the center of oscillation conjugate to the point of contact between the stylus and the record groove.

27. Vibration-translating apparatus comprising a vibratory element, and supporting means for the element comprising arms disposed substantially in planes at an angle to each other and intersecting substantially along a line that constitutes a torsional axis of vibration of the element.

28. Vibration-translation apparatus comprising a stylus; an inductor loop of interrupted-cylindrical-shell form, a cone-shaped stylus support by which the stylus is supported and along the base of which the interrupted-cylindrical loop is secured to provide rigidity, and supporting arms,

one at each end of the interrupted-cylindrical loop.

29. Vibration-translation apparatus comprising an inductor loop of interrupted cylindrical-shell form, a cone-shaped stylus support along the base of which the interrupted-cylindrical loop is secured to provide rigidity, and two supporting arms, one at each end of the interrupted cylindrical loop, the two arms being disposed substantially in two planes inclined to one another and constituting the sole support for the stylus support.

30. Phonographic apparatus comprising a stylus adapted to be disposed in contact with a record groove, combined inductor-and-elastic-supporting means comprising two ribbon members disposed at an angle to each other and providing at the stylus simultaneously a large compliance for transverse motion, a compliance for vertical motion lower than the first-named compliance, and a compliance for longitudinal motion lower than the first two named compliances.

31. Vibration-translating apparatus comprising a vibratory element having conjugate centers of oscillation and adapted to vibrate over a wide range of high and low frequencies, stylus means for applying vibratory impulses at one of the centers, movable-inductor-and-elastic-supporting means for deriving inductively an electric signal from the vibration of the vibratory element and for supporting the element to vibrate about substantially the conjugate center throughout the said range of frequencies in response to the vibratory impulses applied at the said one center, and means for establishing a magnetic field in which the movable inductor means moves.

32. Vibration-translation apparatus comprising a stylus, inductor means, means whereby the stylus is connected to the inductor means, and supporting ribbons for the inductor means comprising sections of warped surfaces, the ratio of transverse to vertical compliance being controlled by the orientation of the warped surfaces.

33. Vibration-translation apparatus comprising a stylus, inductor means, means whereby the stylus is connected to the inductor means, and supporting ribbons for the inductor means comprising sections of warped surfaces, the supporting means comprising arms disposed substantially in planes inclined to each other, and the ratio of transverse to vertical compliance being controlled by the orientation of the supporting members.

34. Vibration-translation apparatus comprising a stylus, a support for the stylus and a combined mechanical-electrical connector-jack for supporting the stylus support and the stylus supported thereby, comprising two tubular mating portions carried by the jack containing mating electrical leads insulated from the mating portions, and means for simultaneously clamping together the mating electrical leads and the mating portions.

35. Vibration-translating apparatus comprising a vibratory element having a vibrational axis determined by the inertia of the element, means for supporting the element, the said vibrational axis being substantially coincident with the vibrational axis determined by the supporting means, movable inductor means for electrically deriving a voltage from the vibrations of the element, and means for establishing a magnetic field in which the movable inductor means moves.
